UNITED STATES PATENT OFFICE

FRANK G. BROTH, OF KOHLER, WISCONSIN, ASSIGNOR TO KOHLER COMPANY, OF KOHLER, WISCONSIN, A CORPORATION OF WISCONSIN

POP-UP WASTE

Application filed August 6, 1926. Serial No. 127,635.

This invention has for its object to provide a waste fitting for sinks and the like, having a pop-up valve operating on the direct lift principle.

5 An object of the invention is to accommodate the offset relation between the operating means and the waste valve so as to insure freedom of movement without loose connections or connections that will work loose or bind or otherwise cause trouble.

10 Another object is to provide such direct lift pop-up waste mechanism that will be adjustable vertically and horizontally to adapt it to varying dimensions.

15 With the above and other objects in view the invention consists in the waste connection as herein claimed and all equivalents.

20 Referring to the accompanying drawings in which like characters of reference indicate the same parts in different views,

Fig. 1 is a vertical sectional view through a waste connection, constructed in accordance with this invention; and

Fig. 2 is a transverse sectional view thereof taken on the line 2—2 of Fig. 1.

In these drawings, 10 indicates a sink or preferably the dish-washer receptacle of a dish-washer and sink combination of porcelain enamelled construction, having a recess 30 or depression in its bottom forming a waste outlet 11 somewhat larger than usual within which is clamped a waste coupling 12 having a flaring funnel-shaped open upper end terminating in a feather edge 13 drawn into close fitting contact with the enamelled surface of the receptacle by a clamping nut 14 threaded on the coupling and engaging the bottom of the receptacle with a gasket therebetween. To the reduced neck of this coupling 12 is threaded a waste housing 15 within which slidably fits a waste plug 16 serving to seal the outlet when in its lower position as shown, but capable of being raised to permit the discharge of water through its ports

40 17 when raised in a manner well known with pop-up waste valves. The housing 15 has an inclined lateral extension carrying at its end a vertical guideway in which a plunger rod 18 fits to have vertical movement, said rod 45 having a working fit in the guide both above

and below the lateral extension of the housing as well as in its passage therethrough and being protected by a packing gland 19 where it passes out of the upper end of the guide. An inclined connecting rod 20 passes 55 through the lateral extension of the housing and connects the waste plug 16 with the plunger rod 18, so that vertical movements of the latter will be imparted to the former. The lower end of this connecting rod projects through an opening in the waste plug and its upper end passes through an opening in the plunger rod where it is clamped by a set screw 21 threaded in the lower end of the plunger rod. This set screw is accessible by removing a screw plug 22 which closes the lower end of the guide. When desired means may be provided for engaging the plunger rod to hold it in its raised position, such means as shown consisting of a 65 spring pressed ball detent contained in a screw plug 23, which is threaded in the wall of the guide, the ball detent thereof being adapted to engage in a recess 24 in the end of the connecting rod 20. 75

Slidably fitting in an opening in the projecting upper end of the plunger rod 18 is an arm 25 which is held in its adjustment by a set screw 26 threaded in the end of the plunger rod, and threaded through the other 80 end of the arm 25 is a vertical adjusting rod 27 held in its adjustment by a set screw 28 in the end of said arm. A connecting rod 29 is pivotally connected with the adjusting rod 27 and with the crank arm 30 of a crank handle 31, so that the turning of the handle 31 produces the necessary vertical movements of the waste plug for opening or closing the outlet. 85

In utilizing a sink or the like container 90 for the purpose of washing dishes, or for cleaning and preparing vegetables, there is likely to be considerable waste matter liable to stop up the strainer of ordinary construction and consequently a special strainer has 95 been designed for this purpose, particularly to permit of the cleaning of the strainer by making it removable in the form of a basket or container for the refuse matter which may be easily lifted out and carried to a garbage 100

receptacle or other place of deposit. Such strainer is shown in the drawing as a basket-like strainer 32 with an upwardly projecting handle 33 by which it may be carried, there being upwardly extending flaring edges to the strainer tightly fitting against the flaring surfaces of the coupling 12. Beneath this strainer is preferably a stationary strainer 34, desirably consisting of a perforated disk 10 resting on an internal flange 35 and also having a handle by means of which it may be removed when desired. The position of the stationary strainer 34 is sufficiently above the waste plug 16 to permit of the vertical movements of the latter without interference.

By means of this invention, the sink outlet may be closed to cause it to retain water for dish washing, vegetable washing or other purposes and when the pop-up valve is open 20 by the turning of the handle the enlarged strainer surface will permit of the quick discharge, notwithstanding the presence of refuse matter, such matter collecting in the removable basket-like strainer 32 which may 25 readily be removed and cleaned and when replaced will tightly fit as a plug in its conical seat.

The removable strainer basket fitting in a recess or depression in the bottom of the 30 sink or other container forms a pocket in the floor of the container into which solid matter may settle and collect during the operation performed while the pop-up waste valve is closed. This solid matter may be removed 35 from the sink either before or after opening the pop-up waste valve. If there are both heavy solids and floating solids present it is preferable to remove the heavy solids first and then replace the strainer basket to collect 40 the floating solids as the water is drained from the container when the pop-up waste valve is opened. In this operation any heavy solids which may have settled into the waste pocket while the strainer basket was removed 45 will be held by the strainer disk 34 and may be removed later.

The construction of the valve operating mechanism is such that there is no possibility of the waste water finding cavities in which 50 to lodge and become foul and there is no chance for it to escape, but the offset plunger rod parallel with the waste plug and coupled therewith affords a tightly packed medium for connection between the waste plug and 55 its lifting mechanism. The detent serves to hold the valve in its open position though this may be effected by the usual offset in the connecting rod 29 permitting the crank handle 31 to pass over dead center. The adjust- 60 ments of the adjusting rod 27 in the arm 25 and the adjustments of the arm 25 in the plunger rod 18 permit of compensation being made for variations in either vertical or horizontal dimensions so that the parts are ex- 65 actly fitted without loose connections and

without parts likely to become loose to require repair.

What I claim as new and desire to secure by Letters Patent is:

1. A pop-up waste valve comprising a 70 housing forming spaced vertical guides with a narrow inclined connection between them, a waste plug having a tubular stem fitting in one guide of the housing and a plunger rod fitting in the other guide of the housing, 75 a connecting rod secured to the plunger rod and engaging in an opening of the stem of the waste plug, a valve seat for the waste plug connected with the housing, and means for lifting the plunger rod to lift the waste 80 plug, the stem of said waste plug being of sufficient length to avoid uncovering the connection between the guides in the open position of the waste plug.

2. A pop-up waste valve comprising a 85 housing forming a pair of vertical guides spaced apart with an inclined connection between them, a waste plug having a tubular stem fitting in one of the guides and extending beyond the connection, a valve seat for 90 the waste plug connected with the housing, a plunger rod mounted in the other guide, a connecting rod connecting the plunger rod with the stem of the waste plug and passing through the connection, and means for lifting 95 the plunger rod to lift the waste plug, the tubular stem of said waste plug extending beyond the connection a greater distance than the travel of the waste plug, whereby said connection is not uncovered thereby. 100

3. A pop-up waste valve comprising a 105 housing forming spaced vertical guides with an inclined connection between them, a waste plug fitting in one guide, a plunger rod fitting in the other guide, a connecting rod 110 passing through the connection and fitting in an opening in the plunger rod, a set screw in the lower end of the plunger rod for engaging the connection, a screw plug fitting in the lower end of the guide for the plunger rod, said connecting rod passing through an opening in the tubular stem of the waste plug, and means for operating the plunger rod. 115

4. In a pop-up waste valve, a housing 115 forming spaced vertical guides with a connection between them, a waste plug fitting in one guide, a plunger rod fitting in the other guide, a connecting rod passing through the connection and engaged with the waste 120 plug and plunger rod, means for operating the plunger rod, and a spring detent engaging the plunger rod for holding it in its raised position.

In testimony whereof, I affix my signature. 125
FRANK G. BROTZ.
